PERFORATING DEVICE

James C. Hendricks, Marengo, Ill., assignor to McGill Metal Products Company, Marengo, Ill., a corporation of Illinois

Filed Jan. 7, 1965, Ser. No. 424,019

3 Claims. (Cl. 30—358)

This invention relates to a device for perforating sheets and more particularly to an improved construction for such a device for perforating sheets for insertion in a ring binder and adapted to be carried in the ring binder.

In many circumstances it is advantageous to have a perforating device, such as a paper punch, which is capable of being carried in a ring binder so that papers may be punched immediately for insertion in the binder. In addition to being more convenient, such a device prevents the loss of important papers since they may be punched and installed in the binder as required. This is especially helpful to students, salesmen and other persons who move from place to place and for whom a conventional hand punch would be too cumbersome to carry.

It is almost essential that the punch itself be constructed out of metal for accurate, long lasting use. On the other hand, metal is expensive and may be too heavy for convenient portability.

Accordingly, it is an object of this invention to provide an improved construction of a device for perforating sheets for insertion in ring binders.

Another object of the invention is to provide a low cost, lightweight perforating device which may be carried in a ring binder.

Still another object of the invention is to provide a perforating device including a punch constructed of metal and a plastic carrying member to which the punch is secured in a manner to permit easy assembly.

A feature of the invention is the provision, in a device for perforating sheet material, of a metal punch having upper and lower plates joined by a hinge, with a punch projection on one plate and an opening in the other. A flat plastic carrying member has a mounting surface for the punch and openings extending therethrough, with the lower plate having portions extending therefrom projecting through the openings in the carrying member and deformable for staking the lower plate to the mounting surface.

Another feature of the invention is the provision, in a device for perforating sheet material as described, of the carrying member having a mounting ear with an opening therein for mounting the device in a ring binder.

Still another feature of the invention is the provision, in a device for perforating sheet material including a pair of hinged plates, of a carrying member having a hinge housing extending above the level of the hinge with a recess therein to receive the hinge.

A further feature of the invention is the provision of a punch having upper and lower hinged plates and a carrying member, with a leaf spring having a perforated base, positioned between the lower plate and mounting surface of the carrying member, and a pair of curved resilient arms extending between the upper and lower plates.

In the drawing:

FIG. 1 illustrates the perforating device constructed in accordance with the invention as used in a ring binder;

FIG. 2 is a perspective view of the perforating device;

FIG. 3 is an exploded view of the device;

FIG. 4 is a sectional view taken along the lines 4—4 of FIG. 2; and

FIG. 5 is a sectional view similar to FIG. 4 showing the device in the perforating position.

In accordance with the invention, a device for perforat-

ing sheets for insertion in a ring binder includes a hinged metal punch having upper and lower plates. The lower plate has a single projection thereon secured by a staked protrusion and the upper plate has a mating punch opening therein for perforating sheets inserted therebetween.

5 The punch is mounted on a substantially flat supporting and carrying member having openings extending therethrough. The lower plate of the punch is disposed flat against a surface of the carrying member and has portions extending therefrom to project through the openings in the carrying member. The portions are deformable for staking the lower plate to the mounting surface. The carrying member contains a raised portion having a recess therein for accommodating the hinge connecting the upper and lower plates of the punch, and a mounting ear for securing the same in a ring binder.

10 A leaf spring having a perforated base and a pair of curved resilient arms is positioned between the lower plate and the mounting surface of the carrying member. The spring is held firmly in position by the lower plate with the staked protrusion on the lower punch plate and a dimple on the carrying member passing through the perforated base. As the plates are moved into the perforating position, the spring is compressed, and the ends of the resilient arms pass through perforations in the lower plate and into a recess in the mounting surface of the carrying member.

15 Referring now to FIGS. 1 through 5 of the drawing, the metal punch 10 of the invention includes an upper plate 12 and a lower plate 13 coupled by a hinge 15. Upper plate 12 has a projecting rim 17 to facilitate the application of pressure to upper plate 12 during the punching operation. The lower plate 13 has one punch projection 19 secured thereon by staked protrusion 22. Opening 21 in the upper plate 12 mates with the punch 19 to cooperate therewith and perforate sheet material inserted therebetween as the upper plate 12 is closed over the lower plate 13.

20 The metal punch 10 is mounted on a plastic carrying member 30 which includes openings 32 and 33 extending therethrough, and mounting surface 31 upon which the bottom plate 13 of the punch 10 is disposed. The mounting surface has a T-shaped recess 34 therein and a boss 35 projecting thereon. The lower plate 13 has perforations 36 and 37 therein, and deformable portions 38 and 39 extending therefrom. The plate 13 is fixed to the mounting surface 31 by extending the portions 38 and 39 through the openings 32 and 33, and then deforming the portions by bending them back against the carrying member 30 as shown by dotted lines in FIG. 2.

25 The carrying member 30 includes a hinge housing 40 extending above the level of the hinge 15, which is molded with a recess 41 therein. Recess 41 receives hinge 15 of the punch 10 to secure the same against upward movement with respect to the carrying member and to limit the upward movement of upper plate 12 as shown in FIG. 2. Integral with the hinge housing 40 is a mounting ear 43 which is provided with an opening 45 therein for mounting in a ring binder as shown in FIG. 1. A raised shoulder 46 on the carrying member 30, delimits the mounting surface 31 and prohibits contact of the upper plate 12 and the lower plate 13, when the plates are moved into the perforating position.

30 The punch includes a leaf spring 50, which has a base 52, perforated with a round opening 53 and an oval opening 54, and a pair of curved resilient arms 55. The base 52 is positioned between the lower plate 13 and the mounting surface 31, and extends through channel 47 in shoulder 46 into the T-shaped recess 34 (FIG. 5) to permit the lower plate 13 to rest flush with the mounting surface 31. The spring 50 is held firmly in place by the lower plate 13, and by the staked pro-

trusion 22 and the boss 35 passing through the oval opening 54 and the round opening 53 respectively.

In using the punch, a piece of sheet material is placed between the upper plate 12 and the lower plate 13, resting on the resilient arms 55 of the spring 50. When the plates are moved into the perforating position, the spring 50 is compressed with the ends of the resilient arms 55 passing through the perforations 36 and 37 in the lower plate 13 and into the cap of the T-shaped recess 34, thereby permitting the upper plate 12 to move toward lower plate 13, until the upper plate engages the raised shoulder 46. Upon completion of the perforating movement, the spring action of the resilient arms 55 raises the upper plate 12 and lifts the sheet material over punch projection 19 thereby permitting easy removal of the sheet material.

It may therefore be seen that the invention comprises an improved construction for a device for perforating sheets for insertion in ring binders with the perforating device itself adapted to be carried in such a binder. The construction provides a device wherein a metal punch is securely mounted in a plastic carrying member resulting in an effective lightweight, low cost, compact and durable unit.

I claim:

1. A device for perforating sheet material for insertion in a ring binder, including in combination, a metal punch having upper and lower plates, said lower plate having a single projection thereon secured by a staked protrusion and said upper plate having a corresponding punch opening therein for perforating sheets inserted therebetween, hinge means joining said upper and lower plates, a substantially flat plastic carrying member having a mounting surface for said punch and openings extending through said member, said mounting surface having a recess and a boss, said lower plate having perforations and portions extending therefrom to project through said openings in said member, said portions being deformable for staking said lower plate to said mounting surface, said carrying member having hinge housing means extending above the level of said hinge means and having a recess therein accommodating said hinge means to prevent upward displacement thereof relative to said carrying member, said member having a mounting ear with an opening therein for mounting the device in a ring binder and a raised shoulder having a channel therein and surrounding said mounting surface thereby prohibiting contact of said upper and lower plates, and a leaf spring having a perforated base and a pair of curved resilient arms, said base being positioned between said lower plate and said mounting surface and extending in said recess in said mounting surface through said channel of said raised shoulder, said spring being held firmly by said lower plate with said staked protrusion and said boss passing through said perforated base, said arms of said spring being compressed when said plates are moved into perforating position, with the ends of said resilient arms passing through said perforations of said lower plate and into said recess of said mounting surface.

2. A device for perforating sheet material including in combination, a metal punch having upper and lower plates, said lower plate having a single projection thereon secured by a staked protrusion and said upper plate having a corresponding punch opening therein for perforating sheets inserted therebetween, hinge means joining

said upper and lower plates, a substantially flat plastic carrying member having a mounting surface for said punch and openings extending through said member, said mounting surface having a recess and a boss, said lower plate having perforations and portions extending therefrom to project through said openings in said member, said portions being deformable for staking said lower plate to said mounting surface, said carrying member having hinge housing means extending above the level of said hinge means and having a recess therein accommodating said hinge means to prevent upward displacement thereof relative to said carrying member, said member having a raised shoulder having a channel therein and surrounding said mounting surface thereby prohibiting contact of said upper and lower plates, and a leaf spring having a perforated base and a pair of curved resilient arms, said base being positioned between said lower plate and said mounting surface and extending in said recess in said mounting surface through said channel of said raised shoulder, said spring being held firmly by said lower plate with said staked protrusion and said boss passing through said perforated base, said arms of said spring being compressed when said plates are moved into perforating position, with the ends of said resilient arms passing through said perforations of said lower plate and into said recess of said mounting surface.

3. A device for perforating sheet material and for insertion in a ring binder, including in combination, a metal punch having upper and lower plates, said lower plate having a single projection thereon and said upper plate having a corresponding punch opening therein for perforating sheets inserted therebetween, hinge means joining said upper and lower plates, a substantially flat plastic carrying member having a mounting surface for said punch, means for staking said lower plate to said mounting surface, said carrying member having hinge housing means including a recess therein for accommodating said hinge means, said member having a mounting ear with an opening therein for mounting the device in a ring binder and a raised shoulder having a channel therein and surrounding said mounting surface thereby prohibiting contact of said upper and lower plates, and spring means being positioned between said lower plate and said mounting surface and extending through said channel of said raised shoulder, means including said lower plate for securing said spring means to said carrying member, said spring means being compressed when said plates are moved into perforating position, so that upon release of said plates said spring means acts to return said upper plate to a non-perforating position relative to said lower plate and clears the sheet material from said punch projection.
